Dyer Cleveland
Letters Patent

The schedule referred to in those letters patent, and making part of the same, containing a description in the words of the said Dyer Cleveland himself, of his improvement in the machine, called a Horse collar block.

To all to whom these presents shall come.

Be it known, that I Dyer Cleveland of Owego in the County of Tioga, and State of New York, have invented a new and useful improvement in the machine called a horse collar block, for the purpose of forming or fashioning horse or hame collars on, and that the following is a full and exact description of the construction and operation of the said machine, as invented or improved by me.

The said machine or collar block may be made of iron or wood, twenty inches long more or less, in the widest place it is sixteen inches more or less, and eight inches thick more or less, the upper part or about one fourth of the thickness of the block is formed to the shape of that part of a collar that is commonly called the roll or rim of the collar; and in the widest place is eight inches, the remaining three fourths of the thickness of the block is made to extend four inches, more or less, all round the upper part that forms the roll or rim of the collar, and is cut or hollowed out in a proper manner to shape or form that part of the collar that is called the head or belly of the collar. In the upper part or surface of the block, there is a channel or groove, cut out three inches wide, and three inches deep, more or less, running lengthwise of the block to within about three inches of the round end of the block, where there is a screw and nut fixed, then there is a piece of wood, three inches square and twelve inches long, more or less, fitted in the said channel or groove in such a manner that it will slide back and forth in said channel or groove,

111
The leather is first put over and round the
block, the screw is then drawn against the end of the sliding
part of wood that passes in the said channel or groove, the
said sliding piece of wood opposite to the screw is formed
to form the small end or top of a collar, and when a collar is
put on the block and the screw turned to draw the sliding
piece against the upper or small end of the collar, and draws it
tight to the block and gives it the desired shape and form so that
it will fit the neck and breast of a horse at the same time it
stretches the collar and takes out all the wrinkles that may be in the
leather and leaves it smooth bosom.

In using said Machine in the first place, after
the collar is stuffed the two ends are brought together, and
confined by means of a rope passing round the collar, between
the roll and pads lengthwise. Then the collar is put on the
block and by turning the screw is drawn tight to the block,
and brings it into shape as far as it can be before it is sewed
together. Then the collar is taken from the block and sewed
together, and again is put on the block and brought into
proper form by the operation of the screw against the sliding
part of said Machine.
